UNITED STATES PATENT OFFICE.

GUSTAV STRUB, OF TOLEDO, OHIO, ASSIGNOR OF ONE-FOURTH TO GEORGE ALVIN HATTERSLEY, OF NORWOOD, OHIO, ONE-FOURTH TO WILL CHESTER HATTERSLEY, OF CINCINNATI, OHIO, ONE-FOURTH TO DAVID EMERY HUNT, OF TOLEDO, OHIO, AND ONE-FOURTH TO ELIJAH BEANS CORNELL, OF PHILADELPHIA, PENNSYLVANIA.

HUB AND SPOKES FOR METAL WHEELS.

1,127,821.

Specification of Letters Patent.

Patented Feb. 9, 1915.

Application filed April 27, 1914. Serial No. 834,598.

To all whom it may concern:

Be it known that I, GUSTAV STRUB, a citizen of the United States, residing at Toledo, in the county of Lucas and State of Ohio, have invented certain new and useful Improvements in Hubs and Spokes for Metal Wheels; and I do declare the following to be a full, clear, and exact description of the invention, such as will enable others skilled 10 in the art to which it appertains to make and use the same; reference being had to the accompanying drawings, and to the letters and figures of reference marked thereon, which form a part of this specification.

15 My invention relates to a metal wheel, more particularly to the hub and spoke portion of such wheel, and is designed to furnish an improved means for securing the hub and the spokes of the wheel rigidly and 20 immovably in fixed relation.

A further object of my invention is to furnish a metal hub of a construction which may be used in connection with wheels having different numbers.—say either 1, 6, 8 or 25 12,—of equally spaced spoke-fastenings.

My invention is also designed to furnish a hub-and-spoke construction in which the hub-ends of the spoke are of cast metal, the remainder of the spoke being a tube connected with the cast hub-end by welding, brazing or the like.

Another object of this invention is to furnish a novel and useful device for rigidly supporting a brake-drum in place upon the 35 tubular spokes of the wheel by means of bolts passing through the spokes, without weakening of or injury to the spokes.

To these ends my device consists of the construction and arrangement of parts hereinafter described, and shown and illustrated in the accompanying drawings, in which—

Figure 1, is a side-elevation of my hub and spokes with a portion of the inner hub-plate broken away; Fig. 2, a vertical sectional-elevation of the same taken on line $\alpha-\alpha$, Fig. 1; Fig. 3, a side-elevation of one of the spokes hereinafter referred to, removed, and Fig. 4, a central longitudinal sectional-elevation of said spoke taken at a 50 right-angle to the side presented in Fig. 3.

Like numerals of reference indicate like parts throughout the drawings.

In the drawings, 1 is the inner and 2 the

outer hub-flange of my wheel, provided with inwardly projecting overlapping flanges 3 55 threaded to take one another, as at 4, and against the outer of which flanges the inner ends of the spokes 5 abut. Centrally through the flange-plates is the usual spindle-opening 6. The annular space between 60 the outer rims of the flange-plates is shaped and adapted to receive between them the inner ends of the spokes of the wheel, and the sides of this space flare inwardly to correspond with the correspondingly flaring 65 sides 7 of the spoke-ends, as shown in Figs. 2 and 4. The inner ends of the spokes of the wheel form equal segments of a circular body conforming to the channel between the flanges of the hub-plates 1—2, the adjoining sides 8 of the spokes meeting on radial lines and flaring outwardly while the inner and outer sides 7 are flared inwardly.

The inner spoke-ends, formed as above described, are formed,—preferably cast,— 75 hollow. Extending between and integral with the walls of the chambered spoke-ends are webs 9, each having, midway between the two end-walls 8, a thimble furnishing a hole 10 which extends between and through 80 the chambers' end-walls 7. Extending across each of the radial end-walls 8 is a semi-cylindrical recess 11 opposed to a corresponding recess in the adjoining end-wall 8, these recesses together forming holes 12 85 12 corresponding to and in circular alinement with the holes 10. When the spoke-ends are assembled in operative form, there is thus formed by the holes 10—12 a circular series of equi-distant bolt-holes,—in the example 90 illustrated in Fig. 1,—twenty-four in number. Through each of the flange-plates are corresponding bolt-holes 13 for bolts 14, there being a bolt-hole for each pair of neighboring spokes. The holes 13 register 95 with an equal number of holes 10 or 12. The bolts 14 pass through both flange-plates and through holes 10 or 12. In the example indicated in Fig. 1, there would be six bolts 14, but it will be seen that by reason of the 100 twenty-four holes 10—12, there may be one or two bolts 14 for each spoke or that there may be either six or eight of the equally spaced bolts.

Formed on the inner and outer sides of 105 each of the spokes is a notch 15, these

notches, together, forming upon the assembled spokes circular channels or grooves which are engaged respectively by an inwardly turned lip 16 at the outer margin of each of the hub-flanges 1—2.

It will now be seen that the spokes and the hubs are rigidly held in immovable relation to each other by the inner end-abutment of the spokes, the contacting wedge-like sides of the spoke-ends, the inwardly flaring sides of the spoke-ends, the clasp of the hub-flanges, the engagement of the bolts 14 with the hub-flanges and the spokes, and the engagement of the lip 16 with the circularly arranged notches 15, as well as by the clasp of the encircling felly at the outer ends of the spokes.

It is necessary that means be provided for securing to the rear wheels of motor-vehicles a brake-drum, and when, as in the present instance, the spokes of the wheel are formed of tubes, special devices must be provided for securing the brake-drum in place without weakening or injuring the spoke. To this end, the spokes of my wheel are bored, transversely to the plane of the wheel, a suitable distance from its axis, as at 17, the hole being through an internal sleeve or thimble 18 extending between the walls of the spoke. This sleeve is preferably integral with the cast portion of the spoke. The bolts which pass through the holes 17 and which secure the brake-drum in place upon the wheel, because of the end-resistance of the sleeve 18 to the stress of the bolt, can not now crush or distort the spoke.

Having described my invention, what I claim and desire to secure by Letters Patent, is—

1. In a device of the described character, a spoke having an integral chambered metal hub-end the walls of which are connected by a web having centrally thereof a thimble

through which and through the side-walls of such chamber is a bolt-hole. 45

2. In a device of the described character, a spoke having a chambered metal hub-end, the end-walls of the chamber being flared outwardly and the side-walls being flared inwardly, and a thimble connecting said side-walls, there being a bolt-hole through said thimble and through said side-walls. 50

3. In a device of the described character, a series of spokes having respectively a chambered metal hub-end, the radial meeting end-walls of the several chambers having across their meeting faces opposed recesses which together form bolt-holes, the side-walls of said several chambers being connected respectively by a thimble through which and through said side-walls is a bolt-hole, said several bolt-holes being equi-distant and in circular alinement. 55 60

4. In a device of the described character, a series of spokes having respectively a chambered metal hub-end, the radial meeting end-walls of the several chambers having in their meeting faces opposed recesses which together form bolt-holes, the side-walls of said chambers being connected respectively by a thimble through which and through said side-walls is a bolt-hole, said several bolt-holes being equi-distant and in circular alinement, combined with a pair of hub-flanges which clamp between them said series of hub-ends, said flanges having a series of corresponding equi-distant bolt-holes which register with an equal number of the several bolt-holes carried by said spoke-ends. 70 75 80

In testimony whereof I affix my signature in presence of two witnesses.

GUSTAV STRUB.
